UNITED STATES PATENT OFFICE.

AXEL ERIKSON, OF ROCKFORD, ILLINOIS, ASSIGNOR TO THE HESS AND HOPKINS LEATHER COMPANY, OF ROCKFORD, ILLINOIS, A CORPORATION OF ILLINOIS.

MACHINE FOR FORMING CUP LEATHERS.

Application filed November 21, 1919. Serial No. 339,629.

To all whom it may concern:

Be it known that I, AXEL ERIKSON, a citizen of the United States, residing at Rockford, in the county of Winnebago and State of Illinois, have invented certain new and useful Improvements in Machines for Forming Cup Leathers, of which the following is a specification.

This invention relates to the manufacture of cup leathers, such as are used on pump pistons and valves of various kinds.

Because of the different conditions under which these cup leathers are used, the requirements as to shape vary considerably, especially as regards formation of the corners and the quality of retaining the cup shape. The requirements in some cases are for rounded corners, in others sharp corners, and in some instances it is imperative that the cup leather shall retain its set shape after removal from the forming machine, while in others this is not so important.

It has been the practice heretofore to manufacture these cup leathers by means of semi-automatic machines employing male and female dies for pressing the blank into cup shape, but so far as I am aware, this method does not produce cup leathers of the desired qualities, nor has the apparatus been of such nature as to insure the production of cup leathers of the different shapes necessary to meet the various conditions and requirements.

I have in the present invention, aimed primarily, to provide generally improved apparatus for producing cup leathers of any desired shape, so as to fully meet the conditions and requirements of the trade. And to this end, my invention contemplates forming the leather blanks to shape in a novel manner, which positively insures the desired results. That is, a sharp, modified or rounded corner cup might be obtained, the fibers of which have been so worked, compressed and solidified as to effectually retain their set position and shape.

Another important object is to provide apparatus for producing cup leathers more quickly and economically than has been heretofore possible.

In furtherance of these general objects, my invention contemplates a simple and novel combination of dies, automatically operated in timed relation for forming a leather blank into the desired cup shape.

An important feature in this regard, is the compressing of the peripheral portion of a cup leather between the inner and outer tapered walls, whereby an acute angle is given to the corners, the permanence and sharpness of which may be regulated by different adjustments for the purpose.

Other objects and attendant advantages relative to various features of my invention will be readily appreciated as the same becomes better understood by reference to the following description when considered in connection with the accompanying drawings, in which—

Figure 1 is a side elevation of a machine embodying my improvements;

Fig. 2, a reduced plan view of the machine in the normal position;

Fig. 3, a plan sectional view taken substantially on the line 3—3 of Fig. 1;

Fig. 4, an enlarged fragmentary sectional view through the dies, showing them in normal position, and a leather blank inserted;

Fig. 5, a similar sectional view showing the first operation of the butt dies closed on the blank;

Fig. 6, shows the second operation, viz. of turning the corner of the blank;

Fig. 7, a fragmentary plan view of the machine in the position of the second operation;

Fig. 8, a sectional view illustrating the third operation; and

Fig. 9, a fragmentary plan view of the die-moving parts in the position of the third operation.

Before entering into a detailed description of the apparatus employed for operating the various dies, a brief description will be given of the several steps performed in shaping a cup leather according to my invention. It will be noted at this point that my invention resides in the provision of suitable apparatus for performing the several steps and operations about to be disclosed, for shaping a cup leather. Consequently, the particular form of apparatus herein disclosed and shown in the drawings for imparting the desired movements are not essential, since any suitable means might be employed to the ends desired.

The first operation in forming a cup according to my improvements is to grip a blank centrally between what I have termed an inside butt die and an outside butt die.

the former of which is of less diameter than the latter and is tapered so as to provide a corner having an acute angle. In this position, the marginal portion of the blank protrudes beyond the periphery of said butt dies. The terms "inside" and "outside" are given to these die members because they respectively engage the inner and outer sides of the transverse end or head of a completed cup leather. The protruding peripheral or skirt portion of the blank is next turned over the corner of the tapered die, preferably by means of a sliding sleeve die, which embraces the outside butt die and moves axially thereof to engage and press said peripheral portion over the corner and against the sides of the tapered die, thus forming the blank to cup shape, but not permanently to shape. The blank is brought to the desired shape by compressing and solidifying the peripheral portion of the cup leather by means of a compression die having an interiorly tapered face corresponding to the taper of the inside butt die, and moving telescopingly over the latter from the back thereof, forcing the sleeve die to recede or withdraw from the cup leather, and by this action compressing said peripheral portion to the extent desired. Simultaneously with this compressing action, the butt dies are forced together with greater pressure to prevent the leather from working around the corner and crowding into the flat of the cup. This insures perfect forming of the corners, and by varying the pressure of the compressing die, the corners may be formed sharp, modified or rounded.

The machine in its present embodiment consists of front and rear upright standards 11 and 12 respectively, suitably tied together and rigidly supporting at their free ends, a pair of horizontal rods or rails 13, which extend forwardly and rearwardly beyond the standards, as plainly shown in the drawings. Upon the forward ends of these rails, I rigidly secure a cross head 14, to which is threadingly secured, centrally between the rails, the shank 15 of the outside butt die 16 mentioned above. By turning the shank 15, the position of the outside butt die 16 may be varied with respect to the compression die for a purpose to be mentioned hereinafter. This die 16 serves in effect as a rigid abutment against which the inside butt die and the compression dies operate. A suitable lock nut 17 is employed for holding the shank 15 and its die against displacement.

A pair of sliding cross heads designated generally by characters 18 and 19, mounted on the rails between the standards 11 and the stationary cross head 14 and slideable lengthwise thereon, are equipped respectively with compression and cup-forming dies, designated generally by characters 21 and 22 respectively, co-axial with the out-

side butt die 16. These cross heads 18 and 19 are connected by means of a one-way connection, such as rods 23 fixed to the cross head 19 and passing freely through openings in the cross head 18 and equipped at the rear of said openings with adjustable stops, such as nuts 24. Thus, the cross head 18 may move toward and from the cross head 19 without affecting the latter, except when moved away therefrom against the stops 24, whereupon both cross heads will move in unison in this direction.

The die 22 as shown in Fig. 4, is simply in the form of a sleeve embracing the die 16 and adapted by movement of the cross head 19 to be advanced telescopingly over said die to turn the corners of the cup, as will be presently mentioned. Similarly the compression die 21 is of sleeve shape, but its interior is formed to provide a cylindrical portion 25, a tapered portion 26 and an abutment 27, and this die is movable telescopingly over the inside butt die 28 mentioned above, which is carried on the end of a plunger 29 slidably passed through the cross head 18 and through a rearmost cross head 31 slidably mounted on the rails 13 at the rear of the standards 12. This plunger is adapted to be pressed forwardly to engage and hold a leather blank 32 against the abutment die 16. The means for so advancing the plunger consists in the present instance, of a lever 33 pivotally mounted upon and intermediate the rear standards 12 and having a roller equipped end 34 adapted to be actuated by a cam 35 fixed to a cam shaft 36, the driving means of which will be described hereinafter. The rear end 37 of the plunger 29 is axially adjustable for a purpose also to be mentioned hereinafter. The cam 35 is adapted to advance the plunger, and the latter is retracted by means of a contractile spring 38 connected at one end to the cross head 31 and at its opposite end to a collar 39 on the plunger. The butt end 41 of the die 28 is slightly concave and the butt end 42 of the die 16 is convex, so that the center of an interposed blank will be dished inwardly when the plunger is advanced to the position shown in Fig. 1. Prior to this first operation, the blank is supported on a suitable table 43 supported from the cross-head 19, having been placed there by the operator or by any suitable feed mechanism. The periphery of the die 28 is tapered at its end portion 44 corresponding to the taper 26 of the die 21 and is cylindrical at its rear end 45. Thus the surfaces 41 and 44 of the die 28 present a relatively sharp corner of an acute angle. The purpose of these features will be presently explained in connection with the operation.

The mechanism for moving the cross heads 18 and 19 and consequently the dies, will now be described. Because of the pres-

sure required in the compressing action, I prefer to employ a toggle-lever mechanism. This consists of the levers 46 and 47, Figs. 1 and 2, pivotally connected at 48 to the cross heads 18 and 31 respectively. These levers are operated from cranks 49 on the shaft 36, through the agency of connecting links 51. The shaft 36 may be driven by any suitable mechanism, but it is preferred to drive it in single revolution movements when feeding by hand. That is, means is provided for automatically stopping the shaft 36 at the completion of each revolution, during which a cup leather is formed.

In the present instance, the shaft carries a fixed gear 52 in mesh with a pinion 53 on the shaft 54 which is adapted to be driven from a pulley 55 through a friction clutch 56. This clutch is thrown in by pressing on the foot lever 57, and when the clutch is thrown out by reverse movement of this lever, a brake 58 will be simultaneously engaged to instantly stop the operation. When the clutch is engaged, the rear end 59 of the foot lever will be held on top of the latch 61, allowing the latter to position a pin 62 in the path of a cam plate 63 on the adjacent link 51, so that when the shaft 36 makes a complete revolution in a counter-clockwise direction, viewing Fig. 1, said cam plate will press the pin 62 and its latch outwardly allowing the lever end 59 to fall under the influence of spring 64, thereby stopping the operation. It will be noted, however, that the operation might be stopped at any time by pressing sidewise on the hand lever 65, which releases the latch 61 and thus allows the lever 57 to throw out the clutch.

From the foregoing, it will be evident that when the machine is put in operation, both the cross head 19 and the plunger 29 will be simultaneously moved. The latter will be pressed forward through the agency of the cam-actuated parts, to engage and hold a leather blank between the butt dies 16 and 28 in the manner shown in Fig. 5. During this movement, the toggle levers will be drawn down as the cranks 49 approach their lowermost position, thereby drawing the cross head 18 rearwardly until it engages the stops 24 and carries with it the cross head 19 to the position shown in Figs. 6 and 7. By this operation the sleeve die 22 presses the outstanding peripheral edge of the blank around the corner of the die 28, to cup shape. This does not, however, compress or fix the leather in this shape, but is simply a preliminary formation so that the cup will be in condition for the final compression and shaping. As the cranks 49 revolve upwardly, the lever 46 will be pressed forwardly, by reason of the cross head 31 being held against lengthwise movement in either direction on the rails 13. At this point it will be noted that compression springs 66 on said rails take the thrust of the compression stroke, but such springs are of such tension as not to yield except under excessive pressure. During the initial and greater part of this forward movement of the head 18, the head 19 remains stationary, the die 22 remaining in the position shown in Fig. 6, until the advancing die 21 in the compression operation, meets it and forces it back off the cup leather, as shown in Figs. 8 and 9. It will be here noted that the cylindrical portion 25 of the die 21 telescopes the previously formed cup leather so as to provide a substantial and close fitting outer die wall, which merges into the tapered wall 26. This latter wall draws the peripheral edge portion of the cup inwardly, so that it conforms to the tapered end 44 of the die 28, whereupon the shoulder 27 engages the outer end of said peripheral portion of the cup and compresses this portion between the inner and outer tapered walls 44 and 26. By this means a very powerful compressing action is obtained, and by reason of the rim portion of the cup being confined between the tapered walls and disposed at an acute angle with respect to the base of the cup, the fibres will be confined to this shape and very forcibly pressed thereto. This compressing operation would not, however, be so effectual for the purposes in mind if it were not for an additional pressure being imparted to the inside butt die 28 for compressing the base or bottom of the cup so as to prevent the leather from working inwardly around the corner under the influence of the compression die 21. I obtain this pressure on the die 28 substantially simultaneously with and during compression by the die 21. It is effected by means of a secondary cross head 67, Fig. 1, slidably supported on rods 68 carried by the cross head 18. This head or abutment 67 embraces the plunger 29 and is adapted to strike against the collar 39 thereon, at the required time. The thrust is cushioned by springs 69 on the rods 68, and the pressure of the die 28 may be increased or diminished, as required, by adjusting the tension of the springs 69, as will be obvious. And in the event that a sharp cornered cup leather is desired, the die 16 will be adjusted closer to the shoulder 27 (Fig. 8), that is, toward the rear of the machine to cause greater compression of the peripheral portion of the cup. At the same time the die 28 must be correspondingly retracted, this being done in the present instance by adjustment of the end piece 37 of the plunger 29. Likewise the tension of the springs 69 would be adjusted to suit the requirements. It will thus be seen that I am able to form cup leathers with the corners either rounded or sharp, or a modification

of these, according to the needs of the particular case. For cup leathers of different diameters, dies of the corresponding size are used.

5 From the foregoing, it will be manifest that during each complete cycle of the machine, one cup leather will be formed, the operation being first to grip a blank between the butt dies, then bend the corner by means 10 of the sleeve die 22, and finally to back off the sleeve die, and compress the peripheral portion of the cup between the tapered inner and outer walls 44 and 46, while at the same time compressing the cup bottom for the 15 purpose of insuring the solidifying and shaping effect desired. In the present case the leather blanks are fed or positioned by hand on the table 43 intermediate the butt dies, but, nevertheless, the operation is comparatively rapid and considerably faster 20 than machines heretofore designed for forming cup leathers.

It is believed that the foregoing conveys a clear understanding of the principles and 25 objects of the invention, and while I have illustrated but a single working embodiment thereof, it should be understood that the same is susceptible of embodiment in various forms and constructions without departing 30 from the spirit and scope of the invention, as expressed in the appended claims, in which—

I claim:

1. Apparatus for forming from a blank of 35 leather a cup-shaped article characterized by a transverse head and an annular skirt, comprising dies for so forming the blank, said dies having internal and external walls which converge toward the open end of the article, and means for axially compressing the skirt by pressure on its outer end while confining the skirt between said die walls.

2. Apparatus for forming from a blank of 45 leather a cup-shaped article characterized by a transverse head and an annular skirt, comprising dies for so forming the blank to cup shape, said dies having internal and external walls which converge toward the open end of the article, and means for axially compressing the skirt by pressure on its outer end while confining the skirt between said die walls, and said dies having complementary concave and convex walls for dishing the head of said blank inwardly.

55 3. In apparatus for forming cup leathers, a tapered inside butt die, means for turning the leather stock over the corner of said tapered die to cup shape, a die having an internal wall and means for axially compressing 60 the peripheral portion of the cup leather between the tapered wall of said die and said internal wall.

4. Apparatus for forming cup leathers comprising an inside and an outside butt die 65 between which a leather blank is adapted to

be interposed and held, a sleeve die embracing the outside butt die and movable telescopingly over the same to turn the peripheral portion of the blank over the corner of the inside butt die, and a second sleeve die 70 embracing the inside butt die and movable telescopingly over the latter for compressing the peripheral portion of the cup, said inside butt die and second sleeve die having complementary faces converging toward the 75 open end of the cup for shaping the peripheral wall thereof while under said compression.

5. In apparatus for forming cup leathers, a tapered inside butt die, a sleeve die for 80 pressing the leather blank around the corner of said tapered die to cup shape, and a compressing die having a tapered interior wall corresponding to the peripheral taper of the inside butt die and movable telescopingly 85 over the latter to axially compress the peripheral portion of the cup between the tapered walls of said dies.

6. In a machine for forming cup leathers, the combination of an inside and an outside 90 butt die between which a blank is adapted to be interposed, the butt end of the inside die being concave and having a tapered periphery converging from said butt end, the butt end of said outside die being convex, means 95 for pressing said dies together to hold an interposed blank with its peripheral edge protruding, means for bending said edge over the corner of the inside die to cup shape, and a compressing die adapted to axially compress 100 the peripheral portion of the cup and having an interior tapered wall substantially conforming to the taper of said inside butt die, whereby said peripheral portion of the cup will be compressed between tapered die 105 walls.

7. In a machine for forming cup leathers, the combination of an inside and an outside 110 butt die between which a blank is adapted to be interposed, the butt end of the inside die being concave and having a tapered periphery converging from said butt end, the butt end of said outside die being convex, means for pressing said dies together to hold an interposed blank with its peripheral edge protruding, means for bending said edge over the corner of the inside die to cup shape, a compressing die adapted to axially compress 115 the peripheral portion of the cup and having an interior tapered wall substantially conforming to the taper of said inside butt die, whereby said peripheral portion of the cup will be compressed between tapered die walls, and means for moving one of said butt dies in a compression action to compress 120 the bottom of the cup simultaneously with the action of said compressing die.

8. In apparatus for forming cup leathers, the combination of inside and outside butt dies between which a leather blank is adapt- 130

ed to be interposed with the peripheral edge protruding, means for turning said edge over the corner of the inside butt die to cup shape, a pressing die movable telescopically over the inside butt die to axially compress the peripheral portion of the cup, and means for relatively adjusting said butt dies with respect to the compressing movement of the compressing die to secure greater or less compression.

9. Apparatus for forming cup leathers comprising an inside and an outside butt die between which a leather blank is adapted to be interposed and held with the marginal portion of the blank protruding, a sleeve die movable telescopically over the outside butt die to turn said marginal portion of the blank over the corner of the inside butt die, to cup shape, and a sleeve die movable telescopically over the inside butt die to axially compress said peripheral portion of the cup.

10. In a machine of the character described, a frame having a guideway, a pair of die carriers mounted to slide on said guideway and each carrying a sleeve die co-axial with respect to the other, one of said dies being a compression die, an inside and an outside butt die co-axial with said sleeve dies and over which the latter are telescopically movable, means for moving the inside butt die axially toward the outside butt die, to hold an interposed leather blank therebetween with its peripheral portion protruding, and mechanism for operating said die carriers to first cause one, a corner-turning die, to turn said peripheral portion of the blank over the corner of the inside butt die and then to move the compressing die in a direction to axially compress said peripheral portion of the cup.

11. In a machine of the character described, the combination of relatively movable dies for forming a leather blank into cup shape, including a compressing die for axially compressing the peripheral portion of a cup, toggle levers connected with said compressing die, yieldable means taking the thrust of said toggle levers, a crank and a link connection therefrom to the toggle levers for operating the same in die compressing and return strokes, and power driven means for rotating said crank including means for automatically stopping the crank at the completion of each revolution.

12. In a machine of the character described, the combination of an inside and an outside butt die normally held in spaced relation, a sleeve die embracing each of said dies and also held in spaced relation, means for relatively moving said butt dies together to grip and hold an interposed blank with the peripheral portion protruding, means for moving the sleeve die embracing the outside butt die telescopically over the same to turn the peripheral portion of the

blank over the corner of the inside butt die, and means for moving the other sleeve die telescopically over the inside butt die to axially compress said peripheral portion of the cup.

13. In a machine for forming cup leathers, an inside and an outside butt die, adapted to hold an interposed blank with the peripheral portion turned over the corner of the inside butt die to cup shape, a compressing die for axially compressing said peripheral portion of the cup, and means for relatively moving said butt dies to compress the bottom of the cup during the compression of the peripheral portion thereof.

14. In a machine for forming cup leathers, an inside and an outside butt die, adapted to hold an interposed blank with the peripheral portion turned over the corner of the inside butt die to cup shape, a compressing die for axially compressing said peripheral portion of the cup, means for moving the compressing die to effect the compressing action, and means actuated by said die-moving means for relatively moving the butt dies to compress the bottom of the cup die during compression of the peripheral portion thereof.

15. In a machine for forming cup leathers, an inside and an outside butt die between and by which an interposed blank is held with the peripheral portion turned over the corner of the inside butt die to cup shape, and a compressing die movable telescopically over both of said butt dies for axially compressing the peripheral portion of the cup between the periphery of the inside butt die and an interior wall of said compressing dies.

16. Apparatus for forming cup leathers comprising an inside and an outside butt die co-axially disposed and adapted for centrally gripping an interposed blank, the inside butt die being of less diameter than the outside butt die, a sleeve die for turning the marginal portion of the blank over the inside butt die, and a compression sleeve die movable over the inside butt die for axially compressing said marginal portion of the blank.

17. Apparatus for forming cup leathers comprising an inside and an outside butt die co-axially disposed and adapted for centrally gripping an interposed blank, the inside butt die being of less diameter than the outside butt die, a sleeve die for turning the marginal portion of the blank over the inside butt die, and a compression sleeve die movable over the inside butt die for axially compressing said marginal portion of the blank, the external surface of said inner butt die and the internal face of said compression die being tapered converging away from the outside butt die.

18. Apparatus for forming from a blank

- 6
- of fibrous material, a cup-shaped article characterized by a transverse head and an annular skirt comprising means for forming the blank to a cup shape in which the 5 corner made by the juncture of the head and skirt forms an acute angle, and means for axially compressing said skirt portion by pressure on its end while confined in said shape.
- 10 19. Apparatus for forming a cup-shaped article from a blank of fibrous material, in-

cluding an annular inside butt die, the peripheral wall of which is tapered and forms with the end a corner having an acute angle; and a compression die having an interiorly 15 tapered wall complementary to the tapered wall of said inside die, said compression die having a shoulder for engaging the outer end of the peripheral wall of said article for axially compressing the same while it is confined between the tapered walls of said dies. 20

AXEL ERIKSON.
